UNITED STATES PATENT OFFICE.

JOHN HARRISON MATTICE, OF CLYDE, KANSAS.

PERMUTATION-LOCK.

1,217,802.

Specification of Letters Patent. Patented Feb. 27, 1917.

Application filed January 24, 1916. Serial No. 73,941.

To all whom it may concern:

Be it known that I, JOHN HARRISON MATTICE, a citizen of the United States, residing at Clyde, in the county of Cloud and State of Kansas, have invented certain new and useful Improvements in Permutation-Locks; and I do declare the following to be a full, clear, and exact description of the invention, such as will enable others skilled in the art to which it appertains to make and use the same.

My invention relates to improvements in locks and more particularly to those of the permutation or combination type, the object of the invention being to provide an extremely simple and inexpensive arrangement of parts which will be applicable to a wide range of uses and which will be highly efficient and durable regardless of the exact use to which it is put.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a central vertical section through my improved lock mechanism showing the same in operative position;

Fig. 2 is a vertical transverse section taken on the plane indicated by the line 2-2 of Fig. 1;

Fig. 3 is a view similar to Fig. 1 showing the parts of the device in released position;

Fig. 4 is a vertical transverse section taken on the plane indicated by the line 4-4 of Fig. 3;

Fig. 5 is a third vertical transverse section taken on the plane of the line 5-5 of Fig. 1;

Figs. 6, 7, 8 and 9 are perspective details of certain parts of the device to be herein after fully described.

In these drawings, a member 1 is shown which may be the usual spindle of a door lock, the shank of a key, the stem for operating an electric switch, or any other device adapted to be turned only by authorized persons. The member 1 is provided with a head 2 having a flat outer end 3 disposed at right angles to the axis of said head and member, the former having therein an axial socket 4 and one or more notches 5 shown in the present embodiment of the

invention as opening through the end 3. Although in most cases the head 2 will be preferably made an integral part of the member 1, it will be readily understood that the head in question might well be formed as a separate part and secured to said member. For the purpose of turning the head 2 in the necessary manner, the arrangement of parts now to be specifically described by reference to the drawings, is employed.

The numeral 6 designates a disk or the like to be secured in any preferred manner to the casing of the mechanism to be operated by the member 1, or to any other appropriate fixed member, it being only necessary that said disk be held against movement. The front side of the disk 6 is provided with a sleeve 7 preferably cast integrally therewith, the axis of said sleeve 7 being alined with the axis of the head 2 as clearly shown. Mounted for rotation in the sleeve 7 and projecting forwardly therefrom an appropriate distance, is a tubular shaft 8 whose rear end is shown as provided with a head 9 having a flat rear end disposed either in contact with or in close proximity to the face 3 of the head 1, said end of the head 9 having formed therein one or more radial notches 10, two of these notches being here shown.

Mounted for rotation and axial shifting in the tubular shaft 8, is a spindle 11 having an appropriate knob 12 on its outer end, while its inner end is equipped with laterally extending projections 13 preferably in the form of pins. These projections are adapted to be received in the notches 10 whereby the member 1 may be turned in the necessary manner, but it is the intention of the improved device to prevent insertion of these projections into said notches by unauthorized persons. In order to accomplish this, the pins 13 are positioned in the notches 10, the shaft 8 is rotated to space the notches 10 circumferentially from those designated at 5, and said shaft is then locked against rotation. As one simple means of locking the shaft 8 against rotation, the drawings illustrate the construction now to be described.

The sleeve 7 is formed with an aperture 14 in its upperside, said aperture necessarily leading from the exterior to the interior of said tube and preferably extending to the free end thereof. Adapted for registration with the aperture 14, is a cavity 15 formed

in the periphery of the tubular shaft 8, said cavity having two of its sides designed to form cam surfaces 16 adapted for a purpose to be set forth. Carried within the 5 aperture 14 and extending beyond the periphery of the sleeve 7 when the device is not in operative position, is a weighted tumbler 17 here shown in the form of a metal cylinder, said tumbler being adapted to drop 10 into the cavity 15 when the shaft 8 is turned to the proper extent, thereby locking said shaft against further movement, provided said tumbler be held against shifting outwardly.

15 For the last named purpose, a plurality of tumbler retaining rings are shown in the drawings, two of these rings being designated at 18, while a third is indicated by the numeral 19. All of these rings rotatably 20 surround the fixed sleeve 7 and are frictionally held thereon. Each one of the three rings is formed with an internal notch 20, all of said notches being adapted for alignment and for registration with the aperture 25 14 as shown in Figs. 3 and 4, whereupon rotation of the shaft 8 will be permitted, since one or the other of the cam surfaces 16 will move the tumbler 17 from the cavity 15. When the notches 20 are not alined, 30 however, the numerous rings will retain said tumbler in the aperture 14 and cavity 15, thus holding the shaft 8 against movement. Obviously, when the last named shaft has been turned the necessary amount, the 35 notches 10 will register with those designated at 5, whereupon inward movement of the shaft 11 will move the pins 13 into said notches 5. Thus, the member 1 may be turned at will.

40 The ring 19 is of greater diameter than the others, said ring being provided with a laterally extending annular flange 21 which surrounds said other rings, the free edge of said flange abutting a circular plate 45 22 which forms with said flange a protective housing for the tumbler 17 and the smaller rings coöperating therewith. The plate 22 is formed with a central opening through which the front end of the tubular shaft 8 passes, said end being provided with a collar 23 permanently secured thereon in any suitable manner, and bearing against the plate 24 to prevent removal of the latter and of parts in rear thereof.

50 For the purpose of operating the rings 18 by actuation of the plate 22, a rigid pin 26 extends from the ring 19 through any desired one of a series of openings 26' in said plate, said pin coöperating with external shoulders 27 on the aforesaid rings 18. The projecting front end of the pin 19 also passes through an opening 26" in a plate 24 mounted on the shaft 8 and capable of being turned thereon to adjust a pointer 24' 55 with which it is provided, before said pin

is inserted into said opening 26". When the plate 22 is rotated until the pointer 24' extends opposite the correct graduation, the notch 20 of one ring 18 will be disposed above the tumbler 17. Rotation of said 70 plate a predetermined extent in the opposite direction, will now properly position the other ring 18, while again reversing its direction of movement and turning said plate to the necessary amount, will position 75 the notch 20 of the ring 19 in alinement with the others. The knob 12 may then be turned and forced inwardly until the pins 13 are received in the notches 5, whereupon the member 1 may be operated as above 80 set forth.

When the improved mechanism is to be locked, or in other words is to prevent movement of the member 1, the knob 12 is pulled outwardly and at the same time turned to 85 again dispose the pins 13 in the notches 10 whereupon further rotation of said knob will move the shaft 8, thereby disposing the aforesaid notches out of alinement with the notches 5 and allowing the tumbler 18 to 90 drop into the cavity 15. Proper actuation of the plate 22 will now so dispose the rings 18 and 19 as to prevent removal of said tumbler from the aforesaid cavity until a legitimate user again operates the device. 95

Preferably, though not necessarily used in conjunction with the numerous novel features above described, is a centrally apertured cap 28 which is passed over the head 2 and threaded into an annular flange or 100 the like 29 formed on the rear face of the disk 6. This detail will retain the head in question in proper relation to the remainder of the device, but obviously its exact structure might vary in a number of ways. 105

From the foregoing description, taken in connection with the accompanying drawings, the construction, manner of operation, and advantages of the improved device will be readily understood without requiring a more extended explanation. In conclusion, I will state that although certain specific details have been shown and described for illustrative purposes, numerous changes may be made within the scope of the invention 110 as claimed without sacrificing the primary 115 advantages thereof.

I claim:

1. In a permutation lock mechanism, the combination of a fixed sleeve having an aperture leading from its interior to its exterior, a shaft mounted for rotation in said sleeve and having in its periphery a cavity for registration with the aforesaid aperture, a tumbler carried in said aperture and adapted for partial reception in the cavity to lock the shaft against rotation, said tumbler projecting beyond the periphery of said sleeve when removed from the cavity, 125 a plurality of rings rotatably surrounding 130

- said fixed sleeve to prevent removal of the tumbler from said cavity, said rings having external shoulders and internal notches, the latter being adapted to be registered with 5 the aforesaid aperture to allow outward movement of said tumbler, a housing for the rings, and an operating member in and carried by said housing for coöperation with the aforesaid shoulders to set the rings 10 when said housing is properly turned.
2. In a permutation lock mechanism, the combination of a fixed sleeve having an aperture leading from its interior to its exterior, a shaft mounted for rotation in 15 said sleeve and having in its periphery a cavity for registration with the aforesaid aperture, a tumbler carried in said aperture and adapted for partial reception in the cavity to lock the shaft against rotation, 20 said tumbler projecting beyond the periphery of said sleeve when removed from the cavity, a plurality of rings rotatably surrounding said fixed sleeve to prevent removal of the tumbler from said cavity, said 25 rings having internal notches to be registered with the aforesaid aperture to allow outward movement of said tumbler, an annular flange extending from one of said rings and surrounding the other rings, a 30 plate abutting one edge of said flange and forming with the latter a housing for the tumbler and the last named rings, and co-operating means carried by the housing and rings for setting the latter when the housing 35 is properly turned.
3. In a permutation lock mechanism, the combination of a fixed sleeve having an aperture leading from its interior to its exterior, a shaft mounted for rotation in said 40 sleeve and having in its periphery a cavity for registration with the aforesaid aperture, a tumbler carried in said aperture and adapted for partial reception in the cavity
- to lock the shaft against rotation, said tumbler projecting beyond the periphery of 45 said sleeve when removed from the cavity, a plurality of rings rotatably surrounding said fixed sleeve to prevent removal of the tumbler from said cavity, said rings having internal notches to be registered with the 50 aforesaid aperture to allow outward movement of said tumbler, an annular flange extending from one of the endmost of said rings and surrounding the other rings, a 55 plate abutting the free edge of said flange and forming with the latter a housing for the tumbler and the last named rings, a rigid pin extending from said endmost ring to the plate, and shoulders on the exterior of the other rings to be engaged by said pin 60 to properly position said rings.
4. In a permutation lock mechanism, the combination of a fixed sleeve, a tubular shaft passing rotatably therethrough and having at one end a notch, permutation 65 locking means coöperating with said shaft and sleeve to lock the former against rotation, a spindle rotatably and slidably mounted in said tubular shaft and having a laterally extending rigid projection for 70 reception in said notch to hold said spindle against rotation when the shaft is locked, and a member to be turned having a head against which the aforesaid projection bears when disposed in said notch, said head also 75 having a notch into which the projection may be moved when rotation of the shaft is allowed by release of the aforesaid locking means.

In testimony whereof I have hereunto set 80 my hand in presence of two subscribing witnesses.

JOHN HARRISON MATTICE.
